UNITED STATES PATENT OFFICE

ARTHUR W. SEYFRIED, OF CLEVELAND, OHIO

DESIGN FOR A WINDOW VENTILATOR

Application filed August 13, 1932. Serial No. 44,599. Term of patent 14 years.

To all whom it may concern:

Be it known that I, ARTHUR W. SEYFRIED, a citizen of the United States, residing at Cleveland, in the county of Cuyahoga and State of Ohio, have invented a new, original, and ornamental Design for Window Ventilator, of which the following is a specification, reference being had to the accompanying drawing, forming a part thereof, in which—

Figure 1 is a perspective view of a win-

dow ventilator embodying the design of the invention.

Figure 2 is another perspective view of the window ventilator taken in the opposite direction of Figure 1.

Figure 3 is a side view of the window ventilator.

I claim:

The ornamental design for a window ventilator substantially as shown.

ARTHUR W. SEYFRIED.
